UNITED STATES PATENT OFFICE.

WILLIAM J. ADDISON, OF ST. LOUIS, MISSOURI, ASSIGNOR OF ONE-HALF TO ALEXANDER K. BOYER, OF ST. LOUIS, MISSOURI.

ROLLER CAR-DOOR HANGER.

1,225,098.

Specification of Letters Patent.

Patented May 8, 1917.

Application filed January 10, 1917. Serial No. 141,614.

To all whom it may concern:

Be it known that I, WILLIAM J. ADDISON, a citizen of the United States, and resident of St. Louis, in the State of Missouri, have invented certain new and useful Improvements in Roller Car-Door Hangers, of which the following is a specification containing a full, clear, and exact description, reference being had to the accompanying drawings, forming a part hereof.

My invention relates to an improved roller car-door hanger, and it consists in the novel construction and arrangement of parts hereinafter described and particularly pointed out in the claim found at the end of this specification.

The object of my invention is to provide an improved roller car-door hanger which shall be of reasonable cost, and at the same time permit the car door to be opened and closed at all times, when not sealed or locked, with certainty and despatch; and which shall do away with the improper "looseness" of the door upon its hangers when in a dry condition, and with all liability to "stick" in a closed position during wet weather, when the lumber composing the door and car (when steel construction is not used) swells and causes the parts to bind together and refuse to operate, in car-doors of ordinary and well-known construction.

In the drawings,

Figure 1 is a side-elevation of a freight-car and its door, having my invention applied thereto.

Fig. 2 is a vertical section, on the line 2—2 of Fig. 1.

Fig. 3 is a detail end elevation of one of my improved track-brackets with the track-rod in section and located in one of the adjusting-slots of said bracket.

Fig. 4 is a front view of the same bracket and track-rod.

Fig. 5 is a detail end elevation of one of my improved bottom track-brackets, as used at the bottom of the car-door.

Fig. 6 is a front view of the same bottom bracket, and

Fig. 7 is an end-elevation of the upper part of the door, having my roller and track-rods thereon.

The numeral 1 designates a common car, which may be of wood or steel construction, with the usual door 2, and other common appurtenances.

Above the door 2 are fixed two straight parallel track-rods 3 and 4, respectively, which pass directly into and through the two horizontal, parallel, slots 5 of the upper track-rod brackets 6; but said rods are adjustably mounted in said slots, so that they may be moved nearer to or farther from the side of the car 1.

To effect the desired adjustment of the track-rods, they are provided with screw-threads 7 at both their ends, and clamping-nuts 8 are mounted upon said threaded portions, so as to tightly clamp the said brackets 6 between said nuts, and thus lock the track-rods in the desired position to permit the door 2 to slide freely at all times, and at the same time to cause the door to closely hug the side of the car and thus prevent the entrance of rain and snow when the door is closed.

Mounted between said parallel track-rods, at the top of the door 2, are the rollers 9 having their peripheries provided with grooved treads which fit and roll upon the said track-rods, which latter are circular in cross-section by preference.

Hanger-plates 10 are bolted on the outside and inner side of the door 2, by means of common bolts 11, so that the outer ends of said plates will project a distance beyond said door, at both its top and bottom, and the rollers 9 are mounted in the spaces between said outer and inner plates upon bolts 13, at both top and bottom of said door.

Rollers are also used to support the weight of the door, as well as to keep it close to the car side, and most of the weight of the door is supported by the rollers at the bottom of the door, which bottom rollers run upon a single lower track-rod 14 adjustably mounted to slide nearer to or farther from the car body in the slots 15 of the lower track-hanger brackets 16.

Said lower brackets are similar in every way to the upper brackets 6, except that the lower brackets are of less length.

Said lower brackets 16 are fixed upon the car by means of common screws or bolts 17 passed through openings 18 in said brackets and engaging the car frame.

The upper brackets are secured to the car in the same way, preferably, by means of the bolts 17.

A common supporting-bracket 19 is secured to the car at about midway of the

length of said lower track-rod 14, to prevent possible sagging or movement of said rod in any direction thereat.

In the operation of my car-door hanger 5 the upper track-rod 3 acts to hold the rollers upon the lowermost one of the pair of track-rods, and prevents any possible derailment of said rollers, and at the same time the upper edges of said rollers are held securely 10 in alinement and thereby prevented from wabbling, with the result that the door 2 is held at just the proper distance from the car for efficient operation.

The rollers 9 at the bottom of the door 2 15 support and simultaneously guide the door at the bottom edge of the same.

When it is found that the door is "stuck" closed, or is too far away from the car side, all that is necessary to remedy the difficulty is to 20 manipulate the track-rod nuts 8, by either loosening or tightening them when the rods 3, 4 and 14 can be quickly adjusted in their slots 5 and 15, and said track-rods may be located farther from or nearer to the car 25 side, as may be required.

Common stock-brackets 20 are fixed on the

side of the car, to form stops to limit the movements of the door at its closed and open positions.

What I claim as my invention is the following:

An improved car-door hanger, comprising a pair of straight parallel track-rods, brackets having parallel horizontal slots into and through which said rods directly 35 pass and are adjustably mounted above the door opening of a car, means for fixing said brackets upon the car, clamping-nuts threaded on said tracks, on opposite sides of said brackets for locking said rods in said slots 40 after adjustment, a suitable door, and rollers having grooved peripheries and running upon said rods at the upper end of said door, in combination with suitable means for supporting and guiding the door at the bottom. 45

In testimony whereof, I have signed my name to this specification, in presence of two subscribing witnesses.

WILLIAM J. ADDISON.

Witnesses:

ALEXANDER K. BOYER,
JOHN C. HIGDON.
